UNITED STATES PATENT OFFICE.

GEORGE ALBERT LYON, OF PHILADELPHIA, PENNSYLVANIA.

VEHICLE BUFFER.

Application filed January 19, 1921. Serial No. 438,295.

To all whom it may concern:

Be it known that I, GEORGE ALBERT LYON, a citizen of the United States, and resident of Philadelphia, county of Philadelphia, 5 State of Pennsylvania, have made a certain new and useful Invention Relating to Vehicle Buffers, of which the following is a specification, taken in connection with the accompanying drawing, which forms part 10 of the same.

This invention relates especially to resilient strip automobile buffers or bumpers which may comprise end loops and connected attaching members to be clamped or 15 secured to the vehicle, while the impact receiving or buffer front members which may be arranged in overlapping reenforcing position may advantageously be bent upward and downward beyond the end loops, 20 so as to form upwardly and downwardly extending contact portions within or adjacent the double strength buffer front. By bending each of the buffer front members alternately upward and downward beyond 25 the general level of the impact receiving member a series of such projecting contact portions may be provided and by more or less intertwining these two bent buffer front portions, still further strength and 30 rigidity may be secured. For many purposes it is sufficient to give each of the overlapping ends of the buffer front members a single downward and upward arched bend, so that when overlapped by the other co- 35 operating front member the buffer front presents a generally intertwined appearance which is more or less preserved when the front members are laterally adjusted to suit different width vehicles. In some cases the 40 ends of these buffer front members may be bent into line with the cooperating connector portions of the other front member which facilitates clamping them together by the use of the usual encircling 45 clamping members.

In the accompanying drawing showing in a somewhat diagrammatic way various illustrative embodiments of this invention.

Fig. 1 is a perspective front view of a 50 buffer; and

Fig. 2 is a corresponding view when the buffer has been adjusted to fit a narrower vehicle.

Figs. 3 and 4 are similar views of other 55 illustrative buffers.

The buffer may advantageously be formed

of tempered spring steel strip which may be one quarter to three eights of an inch thick and one and three quarters to two and one half inches wide more or less and for many 60 purposes two generally similar strips may be formed, each comprising an attaching member, end loop and overlapping impact receiving front member. In the buffer shown in Fig. 1 for example, the front member 2, may be integral with the end loop 3 and the attaching member 4 while the other front member 1 may be integral with the end loop 5 and attaching member 6. As illustrated the front member 2 may be formed 65 with the alternately arranged downwardly and upwardly extending arches 7, 8 which are alternately bent below and above the level of the end loop and connector portion 9 of this buffer element. The other buffer 70 element may have a correspondingly arranged downwardly bend 9, 10 and upwardly extending arch or contact portion 11 adjacent the end connector portion 12, which may extend substantially in line with 75 the end loop and cooperating connector portion 2 of the other buffer strip. Any desired form of clamping or connecting devices may be used to securely connect these 80 buffer elements at the desired points and it is usually advantageous to adjustably connect these parts so as to provide a sufficient width adjustment of the attaching members to accommodate different width automobile 85 frames. For this purpose the enclosing 90 clamping members 13, 14 may be secured around the relatively straight or aligned connector portions of the strip, so that they are firmly secured in overlapping reenforcing cooperation so that the upwardly and 95 downwardly projecting contact portions are strongly supported to resist collision impact. At the same time these parts may be adjusted throughout a range of several 100 inches or more and Fig. 2 shows such an adjustment for a narrower automobile frame where the parts still have a generally intertwined or interlooped appearance from the front, the meeting point 24 of the upper edges of the strip in the center being somewhat lower than in the symmetrical mid-position shown in Fig. 1.

Fig. 3 shows another illustrative buffer in which the front member or strip 15 has generally similar downward and upward arched portions 17, 18, the connector end 19 being however left in oblique position so 105

as to extend diagonally across the cooperating connector portion of the other front member 16. This other front strip 16 may have the bent or sinuously curved contact portions 21, 22, while its end connector portion 23 may also be angularly arranged as indicated. U-bolt connector or clamping devices such as 20 are desirable for this type of construction especially when the reinforcing front portions are sufficiently bent around each other or intertwined so that both the inclined connection portions are arranged back of the other relatively straight strips 15, 16. These U-bolt clamping devices which may extend through holes in these connector ends 19, 23 may have the tighteners 25 to securely clamp the parts in adjusted position, the point of intersection 24 varying somewhat with the lateral adjustment of the parts as in the previous case.

Fig. 4 shows still another arrangement in which the sinuously bent overlapping portions of the front members are formed separately and bolted or clamped to the other parts which somewhat facilitates manufacture and shipping. In this case the front connector portion 26 terminates in the end 27, while the other end loop 5 has a similar straight connector portion 27, 28. The double reenforcing front elements may comprise substantially straight connector portions 29, 39, while the strip element may have the bent contact portions 30, 31 extending below and above the level of its connector portions and also the end loops of the elements to which it may be connected. The other sinuous element to which these parts may be connected may comprise the connector portions 32, 35 and the bent contact portions 33, 34, these parts being preferably intertwined or twisted around each other as indicated which promotes the close engagement adjacent the point 38. Any suitable clamping or connecting devices such as 36, 37 or even wider enclosing clamps if desired may be used to securely connect all of these cooperating connector portions in desired adjusted position and with this arrangement, width adjustment may be secured without in any way altering the contour of the intertwined front portions of the buffer.

This invention has been described in connection with a number of embodiments, forms, proportions, parts, arrangements, materials, methods of connection and use, to the details of which disclosure the invention is not of course to be limited, since what is claimed as new and what is desired to be secured by Letters Patent is set forth in the appended claims:

1. The automobile buffer consisting of two integral spring steel strips having greater vertical width than thickness and each comprising an attaching member, an

intermediate end loop and an impact receiving buffer front member arranged in overlapping reenforcing cooperation with the other front member of the buffer, each of said buffer front members being sinuously bent adjacent its ends to form two contact portions extending respectively upward and downward beyond the level of its end loop and having its end connector portion bent substantially into line with the cooperating connector portion of the other buffer front member, one of said end portions being twisted around the other buffer front member and encircling clamping members rigidly connecting said cooperating connector portions in laterally adjusted position. 70

2. The automobile buffer consisting of two integral spring steel strips having greater vertical width than thickness and each comprising an attaching member, an intermediate end loop and an impact receiving buffer front member arranged in overlapping reenforcing cooperation with the other front member of the buffer, each of said buffer front members being sinuously bent adjacent its end to form two contact portions extending respectively upward and downward beyond the level of its end loop and means rigidly connecting said cooperating connector portions. 80

3. The automobile buffer consisting of two integral resilient flat steel strips having greater vertical width than thickness and each comprising an attaching member, an end loop and an impact receiving buffer front member arranged in overlapping reenforcing cooperation with the other member of the buffer, each of said buffer front members being formed adjacent its end with bent contact portions extending upward and downward beyond the level of its end loop and clamping members detachably and rigidly connecting said cooperating connector portions in laterally adjusted position. 90

4. The automobile buffer consisting of two integral resilient flat steel strips having greater vertical width than thickness and each comprising an attaching member, and an impact receiving buffer front member arranged in overlapping reenforcing cooperation with the other front member of the buffer, each of said buffer front members being formed with bent contact portions extending upward and downward beyond the level of its end and clamping members detachably and rigidly connecting said cooperating connector portions. 100

5. The automobile buffer formed of resilient steel strip having greater vertical width than thickness and comprising attaching members, end loops and impact receiving buffer front members arranged in overlapping reenforcing cooperation with each other, each of said buffer front members being sinuously bent to form a plurality of contact 110

portions extending upward and downward beyond the level of its end loop and having its end connector portion bent substantially into line with the cooperating connector portion of the other buffer front member and clamping members rigidly connecting said cooperating connector portions and provide for lateral adjustment.

6. The automobile buffer formed of resilient steel strip having greater vertical width than thickness and comprising attaching members, end loops and impact receiving buffer front members arranged in overlapping reenforcing cooperation with each other, each of said buffer front members being bent to form a plurality of contact portions extending upward and downward beyond the level of its end loop and clamp-

ing members rigidly connecting said cooperating connector portions.

20

7. The automobile buffer formed of resilient steel strip having greater vertical width than thickness and comprising end loops and integral impact receiving buffer front members arranged in overlapping reenforcing cooperation with each other, each of said buffer front members being formed with bent contact portions extending alternately upward and downward beyond the level of its end loop portion and having an end portion bent substantially into line with the cooperating connector portion of the other buffer front member and connecting members rigidly connecting said cooperating connector portions.
